Inventor:
Harry A. Douglas.
By G. L. Gray, C. M.

UNITED STATES PATENT OFFICE.

HARRY A. DOUGLAS, OF BRONSON, MICHIGAN.

REFLECTING-LAMP.

1,261,789.

Specification of Letters Patent.

Patented Apr. 9, 1918.

Application filed April 4, 1917. Serial No. 159,730.

To all whom it may concern:

Be it known that I, HARRY A. DOUGLAS, citizen of the United States, residing at Bronson, in the county of Branch and State 5 of Michigan, have invented a certain new and useful Improvement in Reflecting-Lamps, of which the following is a full, clear, concise, and exact description.

My invention relates primarily to reflecting lamps of the variety known as spot lights, though features thereof are not to be restricted to such lamps, and has for its general object the provision of an improved construction and assembly of certain component parts of a reflecting lamp structure.

One of the features of my invention embraces a reflector carrying casing, a light source holder, and a handle (virtually constituting a continuation of the casing) which 10 is supported upon the light source holder and is desirably instrumental in effecting the assembly of this holder with the casing, the means for effecting this assembly of the holder with the casing being also instrumental in constituting the handle itself virtually a continuation of the casing.

There is also preferably employed a bracket which is desirably assembled with the casing by the coöperation of the handle or other 15 element and the light source holder.

I will explain my invention more fully by reference to the accompanying drawings showing preferred embodiments thereof and in which Figure 1 is a side elevation, partially in section, of a reflecting lamp containing features of my invention; Fig. 2 is a longitudinal view, partially in section and partially in elevation, of portions of the structure illustrated in Fig. 1; Fig. 3 is a 20 view in elevation of a part of the structure shown in Fig. 2; Fig. 4 is a view on line 4-4 of Fig. 2; Fig. 5 is a view, partially in elevation, partially in section, of a modification of the structure shown in Fig. 1; Fig. 45 6 is a view, partially in section and partially in elevation, of a part of the structure of Fig. 5; and Fig. 7 is a view on line 7-7 of Fig. 5.

Like parts are indicated by similar characters of reference throughout the different figures.

The concave reflector 1 of the structure may be distinct and separate from the re-

flector containing casing 2 as in the structure shown in Figs. 1 and 2 or it may be 55 the interior surface of the reflector containing casing, this surface being suitably polished or formed to have the desired capacity for reflection. The reflector carrying casing includes a rearwardly extending cylindrical 60 tubular continuation 3 that constitutes a holder or mounting for the light source. A spring tongue 4 is integrally formed with a shell 5 that constitutes a holder for contact carriers, this spring tongue having ample clearance at its side margins to permit it freely to function. Some part of the tongue, such as the rear free end thereof, has a part 6 projecting therefrom which is narrower than the balance of the tongue and is 70 slightly narrower than a slot 7 in the holder 3 whereby this portion may project into the slot while at the same time the side margins of the tongue 4 are adapted to press against the side margins of the slot 7. The tongue 75 thus presses upon a surface of the holder 3 and, where there is but one tongue, forces the shell toward the opposite side of the holder whereby the shell is held in engagement with the holder 3. The slot 7 is elongated so that the shell 5 may be moved back and forth in its holder 3 whereby in the 80 structure illustrated the position of the lamp bulb 8 which is carried by the forward end of the shell in front of the reflector may be 85 adjusted with respect to the reflector. The base 9 of the lamp bulb 8 constitutes a forward contact carrier and as the arrangement illustrated in a double pole arrangement this contact carrier 9 carries two rear contacts 90 10 and 11. The lamp base or contact carrier 9 is provided with bayonet pins 12 engageable within bayonet seats 13 constituting parts of bayonet slots 14. The rear contact carrying plug 15 within the casing 2 is provided with terminal blocks 16 having binding screws 17 by which circuit wires may be secured to the terminal blocks. These terminal blocks are cylindrical and the forward ends thereof are tubular, springs 18 being included in the tubular portions of the 95 terminal blocks and operating to press contacts 19, 20 forwardly into engagement with the contacts 10 and 11, all of these contacts being within the casing. The springs 18 and 100 the contacts 19 and 20 thus not only serve to

establish circuit for the lamp but also operate to hold the lamp base 9 in bayonet pin and slot connection with the shell 5.

The plug 15 is rotatable in order that it 5 may perform its switching function and when thus movably mounted it is provided with bayonet pins 21 and which are receivable in alternate bayonet seats 22, 23, the plug being inserted from the front end of 10 the shell with its pins passing along the bayonet slots 14 until they are in the zone that includes the bayonet seats 22, 23 whereafter the base of the lamp bulb is inserted in the shell with its pins 12 placed in the 15 bayonet seats 13. The springs 18 thus not only serve to hold the bayonet pins 12 in the seats but also serve to hold the bayonet pins 21 in the seats to which they are adjusted.

The complementary switching contacts 10 20 and 19 are eccentric with respect to the shell as are also the complementary switching contacts 11 and 20 so that as the plug is turned these contacts are either brought into engagement or are separated according to the 25 direction of movement of the switching plug 15. When the lamp is in open circuit the contacts 19 and 20 are pressed against the insulating portions of the lamp base that are adjacent the contacts 10 and 11, 30 the springs 18 continuing to press the contacts 19 and 20 forwardly to maintain the bayonet pins upon the switching plug and upon the lamp base in their respective bayonet seats. The shell and the parts within 35 it are in front of the casing 2 and in order that the switching plug 15 may be turned or otherwise moved with respect to the lamp base to cut the lamp in and out of circuit, I employ a motion transmitting connection, 40 in the form of a switching rod 24, which is connected at its inner end with the switching plug and which is operable from the exterior of the casing. The outer end of this switching rod desirably has a gripping head 45 piece 25 assembled therewith by means of a pin 26. This head piece may be gripped in order that the rod 24 may be turned into on or off circuit positions and may be moved in and out to adjust the bulb.

50 The switching mechanism which I have described is claimed in my co-pending application, Serial No. 149,660, filed February 19, 1917. Other features of novelty not herein claimed form the subject matter of 55 my co-pending application Serial No. 149,670, filed February 19, 1917.

The holder 3 has a forward flange 26 which is engaged with the front face of the 60 separately formed reflector 1 (in the construction shown in Figs. 1 and 2) or is engaged with the front face of the casing 2 (in the construction shown in Figs. 5 and 6). The handle 27 is carried upon the holder 3 and is desirably engaged therewith 65 through the intermediation of the comple-

mental threaded formations upon the holder and handle. The front end of the handle carries a flange 28, the casing 2 being interposed between the flanges 26 and 28 as is also the separately formed reflector 1 in 70 the construction shown in Figs. 1 and 2, these flanges serving to hold this separately formed reflector and casing 2 in assembly. In the construction shown in Figs. 5 and 6 the flanges 26 and 28 are closer together 75 but in all forms of the structure these flanges co-operate with the holder 3 to hold the handle portion 27 and the reflector containing portion 2 of the casing in assembly. The handle is enlarged at the rear end of 80 the holder 3 so that there is ample clearance affording freedom for assembling movements and whereby suitable space is afforded in which the conductors 29 that lead to the switching plug 15 may be disposed 85 and in which space the inner ends of the conductors may readily move when switching occurs.

The interiors of the casing and handle are 90 merged into one in which composite interior the light source is disposed (together with the reflector in the construction shown in Figs. 1 and 2) and in which space the light source may be adjusted and in which the focusing and switching rod 24 may be 95 moved and into which the head piece 25 may project to the extent required to secure the desired focal adjustment of the lamp, said switch being rotatable in any of its positions to enable the switching of the lamp into and 100 out of circuit.

The portion 30 of the bracket 31 is interposed between the flange 28 and the reflector carrying portion 2 of the casing, the flange 28 being screwed into tight engagement 105 with the bracket portion 30 by turning the handle 27. In the form of the invention illustrated in Figs. 1 and 2 the flanges 26 and 28 are enabled to assemble the separately formed reflector 1, the reflector containing casing 2, and the bracket 31 and as 110 these flanges are respectively provided upon the light source holder 3 and the handle 27 this handle and holder are included in the assembly that is effected by said flanges. 115 In the form of the invention shown in Figs. 5 and 6 the flanges 26 and 28 are very closely approached, the casing 2 and the bracket portion 30 being respectively directly engaged by the flanges 26 and 28 while the 120 bracket portion 30 is clamped between the flange 28 and the exterior of the casing 2. The forward portion of the handle 27 thus, with its flange 28, constitutes a clamping 125 nut to clamp the bracket in engagement with the casing. To prevent the handle 27 from turning loose the construction shown in Figs. 6 and 7 may be employed. The flange 28 may carry a holding screw 32 which may be screwed into some threaded 130

opening 33 in the bracket portion 30 near which the hole in the flange 28 (that is to receive the screw) stops when the flange 28 is clamped home.

5. The lower end of the bracket 31 is in ball and socket connection with a split anchorage 34 between the split parts of which the lower end of the bracket is clamped by a clamping bolt 35. The clamp 34 is clamped 10 to any suitable support, such as the wind shield 36, by clamping screws 37. By means of this bolt 35 the clamp may be loosened to enable the lamp to be placed in any selected adjustment and may thereafter be 15 tightened to maintain this adjustment.

While I have herein shown and particularly described the preferred embodiment of my invention I do not wish to be limited to the precise details of construction shown as 20 changes may readily be made without departing from the spirit of my invention, but having thus described my invention I claim as new and desire to secure by Letters Patent the following:—

25. 1. In a reflecting lamp, the combination with an electric lamp bulb; of a holder for supporting the electric lamp bulb; a reflector carrying casing; a handle engaged with the holder and coöperating therewith to maintain 30 the handle and holder in assembly with the casing; a shell, supported by the aforesaid holder, in which shell the electric lamp bulb is mounted and which is movable longitudinally of the holder to afford focal adjustment; and a rotatable switching plug 35 coupled with the shell and serving to switch the lamp bulb into and out of circuit, this plug being operable from the exterior of the lamp structure.

40. 2. In a reflecting lamp, the combination with an electric lamp bulb; of a holder for supporting the electric lamp bulb; a reflector carrying casing; a handle in threaded engagement with the holder and coöperating therewith to maintain the handle and holder in assembly with the casing; a shell, supported by the aforesaid holder, in which shell the electric lamp bulb is mounted and which is movable longitudinally of the 45 holder to afford focal adjustment; and a rotatable switching plug coupled with the shell and serving to switch the lamp bulb into and out of circuit; this plug being operable from the exterior of the lamp structure.

55. 3. In a reflecting lamp, the combination with an electric lamp bulb; of a holder for supporting the electric lamp bulb; a reflector carrying casing; a handle in threaded engagement with the holder and coöperating therewith to maintain the handle and holder in assembly with the casing, the front ends of the handle and holder having flanges between which the casing is disposed; a shell, supported by the aforesaid holder, in 60 which shell the electric lamp bulb is mount-

ed and which is movable longitudinally of the holder to afford focal adjustment; and a rotatable switching plug coupled with the shell and serving to switch the lamp bulb into and out of circuit, this plug being operable 70 from the exterior of the lamp structure.

4. In a reflecting lamp, the combination with an electric lamp bulb; of a holder for supporting the electric lamp bulb; a reflector carrying casing; a lamp supporting bracket; a clamping member coöperating with said holder to maintain the bracket and casing in assembly; a shell, supported by the aforesaid holder, in which shell the 80 electric lamp bulb is mounted and which is movable longitudinally of the holder to afford focal adjustment; and a rotatable switching plug coupled with the shell and serving to switch the lamp bulb into and 85 out of circuit, this plug being operable from the exterior of the lamp structure.

5. In a reflecting lamp, the combination with an electric lamp bulb; of a holder for supporting the electric lamp bulb; a reflector carrying casing; a lamp supporting bracket; a clamping nut in threaded engagement with the holder and coöperating with said holder to maintain the bracket and casing in assembly; a shell supported by the 90 aforesaid holder, in which shell the electric lamp bulb is mounted and which is movable longitudinally of the holder to afford focal adjustment; and a rotatable switching plug coupled with the shell and serving to switch 95 the lamp bulb into and out of circuit, this plug being operable from the exterior of the lamp structure.

6. In a reflecting lamp, the combination with an electric lamp bulb; of a holder for supporting the electric lamp bulb; a reflector carrying casing; a lamp supporting bracket; a clamping nut in threaded engagement with the holder and coöperating with said holder to maintain the bracket and casing in assembly, the forward end of said holder being provided with a flange, the casing and the bracket being interposed between said flange and the nut; a shell supported by the aforesaid holder, in which 105 shell the electric lamp bulb is mounted and which is movable longitudinally of the holder to afford focal adjustment; and a rotatable switching plug coupled with the shell and serving to switch the lamp bulb into and 110 out of circuit, this plug being operable from the exterior of the lamp structure.

7. In a reflecting lamp, the combination with a light source; of a holder for supporting the light source; a reflector carrying 115 casing; a handle engaged with the holder and coöperating therewith to maintain the handle and holder in assembly with the casing; and a shell, supported by the aforesaid holder, in which shell the lamp element is 120

- 4
- mounted and which is movable longitudinally of the holder to afford focal adjustment.
8. In a reflecting lamp, the combination with a light source; of a holder for supporting the light source; a reflector carrying casing; a handle in threaded engagement with the holder and coöperating therewith to maintain the handle and holder in assembly with the casing; and a shell supported by the aforesaid holder, in which shell the lamp element is mounted and which is movable longitudinally of the holder to afford focal adjustment. 5
9. In a reflecting lamp, the combination with a light source; of a holder for supporting the light source; a reflector carrying casing; a handle in threaded engagement with the holder and coöperating therewith to maintain the handle and holder in assembly with the casing, the front ends of the handle and holder having flanges between which the casing is disposed; and a shell supported by the aforesaid holder, in which shell the lamp element is mounted and which is movable longitudinally of the holder to afford focal adjustment. 10
10. In a reflecting lamp, the combination with a light source; of a holder for supporting the light source; a reflector carrying casing; a lamp supporting bracket; a clamping member coöperating with said holder to maintain the bracket and casing in assembly; and a shell supported by the aforesaid holder, in which shell the lamp element is 15
- 20
- 25
- 30
- 35
- mounted and which is movable longitudinally of the holder to afford focal adjustment.
11. In a reflecting lamp, the combination with a light source; of a holder for supporting the light source; a reflector carrying casing; a lamp supporting bracket; a clamping nut in threaded engagement with the holder and coöperating with said holder to maintain the bracket and casing in assembly; and a shell supported by the aforesaid holder, in which shell the lamp element is mounted and which is movable longitudinally of the holder to afford focal adjustment. 40
12. In a reflecting lamp, the combination with a light source; of a holder for supporting the light source; a reflector carrying casing; a lamp supporting bracket; a clamping nut in threaded engagement with the holder and coöperating with said holder to maintain the bracket and casing in assembly, the forward end of said holder being provided with a flange, the casing and bracket being interposed between said flange and the nut; and a shell supported by the aforesaid holder, in which shell the lamp element is mounted and which is movable longitudinally of the holder to afford focal adjustment. 45
